HANGER FOR STORM SASHES AND SCREENS

George Hummer, Buffalo, N. Y.

Application January 14, 1942, Serial No. 426,739

3 Claims. (Cl. 16—171)

This invention relates to improvements in hangers for storm sashes, screens and the like and more particularly the invention is concerned with hangers of the kind which, when employed in connection with storm sashes, are adapted to permit the latter to be adjusted in the window casings in which they are installed to positions which will provide for and promote the circulation of air between their marginal edges and the walls of the casings.

One object of the invention is to provide a hanger which is inexpensive in design, simple to apply and which will enable a storm sash or screen to be hung, opened (in the case of a storm sash) and removed with facility.

A further object is to provide a hanger which does not detract from the appearance of the window casing, the parts carried by the casing being so located that they are inconspicuous and are protected to a substantial degree from the elements.

A still further object is to provide a hanger which will enable the securement of a storm sash in an open position in such a manner that vibration will be prevented.

The invention is illustrated in the accompanying drawing in which:

Figure 1 is a front elevational view of storm sash hung in a window casing with hangers embodying the features of the invention.

Figure 2 is an enlarged vertical section taken along line 2—2 of Figure 1, the sash being shown in full lines in a closed position and in dotted lines in the position to which it must be swung before it can be removed.

Figure 3 is a similar section wherein the sash is illustrated in its normal open position.

Figure 4 is a horizontal section taken along line 4—4 of Figure 3.

Figure 5 is a vertical section taken along line 5—5 of the same figure.

Figure 6 is a plan view of a blank from which the lower sash fastening is formed.

Figure 7 is a similar view of a blank from which the hanger is formed.

Figure 8 is a perspective view of the hanger.

Figure 9 is a similar view of the lower fastening.

A pair of hangers, indicated generally at 10 and 11, is illustrated in Figure 1 in connection with a storm sash 12, the frame 13 in which the said sash is hung being of conventional construction and including a head casing 14, horizontal and vertical blind stops 15 and 15a, respectively, and a sill 16. Each hanger includes an angle

member 17 having a horizontal top section 18 which is secured to the under side of the head casing and a depending back section 19 which is secured to the front face of the blind stop 15, suitable holes 20 being formed in the said sections to accommodate attaching screws 21.

A continuous transversely extending slot 22 is formed in the top and back sections of each angle member, preferably substantially midway between the ends of the latter. The portion 23 of the slot formed in the top section of the angle member is narrow at its outer end and flares slightly at its inner end toward the juncture of the top and back sections, the flared end of the narrow portion of the slot being bounded by upwardly extending projections 24 and the portion 25 of the slot formed in the back section of the angle member being enlarged and communicating with the flared end of the narrow portion of the slot.

The slots 22 accommodate screws 26 which are carried by the top cross member 27 of the sash 12. The heads 28 of the said screws are spaced from the member 27 by shanks 29, mortises 30 being formed in the head casing 14 and blind stop 15 to accommodate the angle members 17 and the screws 26. In the closed position of the sash (full-line position in Figure 2) the shanks of the screws 26 engage the outer ends of the narrow portions of the slots 22 to hold the upper part of the sash against the blind stops, any suitable means being employed to hold the lower part of the sash in place.

The sash may be opened when desired, assuming the securing means for the lower part has been released, by pushing the lower part outwardly until it clears the sill 16. The sash may then be lowered until the heads 28 of the screws rest upon the top sections of the angle members 10 in front of upwardly and rearwardly inclined shoulders 31 provided by the projections 24 (see Figure 3). To cooperate with the hangers 10 and 11 in securing the sash in its open position a fastening 32 is secured to the lower horizontal frame member 33 of the sash substantially midway between the sides thereof. The said fastening is in the form of an angle member and has a vertical back section 34 which is secured to the rear face of the frame member 33 and a horizontal forwardly extending bottom section 34a which is secured to the under side of the frame member, suitable holes 35 being formed in the said sections to accommodate attaching screws 36 (Figure 5). A continuous elongated slot 37 is formed in the back and bottom sections of the

fastening preferably midway between the ends of the latter. The portion 38 of the slot which is formed in the section 34 is narrow while the portion 39 which is formed in the section 34a is enlarged, the narrow and enlarged portions of the slot communicating with one another at the juncture of the two sections of the fastening.

As the sash 12 is lowered in the manner described the head 40 (Figure 3) of a screw 41 which is carried by the front face of the sill 16 enters the enlarged portion 39 of the slot 37 in the fastening and the shank of the screw enters the narrow portion 38 of the slot, a mortise 43 being formed in the sash member 33 to accommodate the fastening and the head of the screw. Preferably the screw 41 is adjusted so that as the heads of the screws 26 of the hangers 10 and 11 are seated upon the angle members 17 in front of the projections 24, the head of the screw 41 acts against the walls of the fastening 32 at opposite sides of the narrow portion of the slot 37 to wedge the lower sash member 33 against the outer face of the sill. The sash, therefore, will be secured firmly against vibration, or rattling, in an open position in which substantial clearances are provided at its top and along its sides for the circulation of air.

The sash may be removed, assuming it is secured in the open position illustrated in Figure 3, by elevating it to disengage the fastening 32 from the screw 41 and then swinging it outwardly to the dotted-line position indicated in Figure 2. When the sash occupies such an angular position it may be moved edgewise in the direction of the window casing while being elevated slightly to cause the heads of the screws 26 to ride up, or pass over, the projections 24. When the heads of the screws pass behind the said projections the sash may be lowered slightly and moved edgewise in substantially the same plane to withdraw them through the enlarged portions of the slots 22, thereby disconnecting the screws from the angle members 17.

Referring to Figures 2 and 3, it will be noted that regardless of the angular position of the sash or the manner in which it is elevated and lowered during opening and closing operations it cannot become detached until it is first swung outwardly to an angular position substantially beyond its normal open position. For example, any movement, whether by accident or otherwise, of the top frame member 21 of the sash toward a position to move the heads of the screws 26 behind the projections 24 and toward the enlarged portions of the slots 22 when the sash occupies any normal angular position, will cause the rear corners of the top frame member to engage the blind stops 15a and arrest such movement. Such engagement of the upper corners of the sash with the blind stops will always occur unless the sash is first swung outwardly substantially beyond any angular position which it may be caused to assume in adjusting it from a closed position to an open position, or vice versa. Accidental or unintentional detachment of the sash is thus prevented.

A comparison of the angle members 17 of the hangers 10 and 11 and the fastening 32 (see Figures 8 and 9) illustrates the permissible similarity in design of these parts, the fastening differing from the angle members of the hangers only in the respect that the narrow portion of the transverse slot is of a uniform width and in the respect that the projections at the entrance to the narrow portion of the slot have been

omitted. Referring to Figure 6, which shows a punched blank from which a fastener may be formed and to Figure 7 which illustrates a similar blank from which an angle member of a hanger may be formed, it will be noted that in the case of the latter the narrow portion of the transverse slot tapers toward its entrance to provide wings 44. The latter, when bent along the lines 45, will provide projections 24 of the desired elevation. It is understood, of course, that any desired type of fastening may be employed in connection with the hangers 10 and 11 and that illustrated is intended by way of example only.

I claim as my invention:

1. A hanger which is adapted to be secured to the header of a window casing for cooperation with the shank and head of an element carried by a top part of a frame of the character described, said hanger being angular, being adapted to be attached to said header in such a manner that one section is substantially horizontal while another section is substantially vertical, and being formed with a slot having narrow and enlarged communicating portions located respectively in the horizontal and vertical sections of said member, the shank of said element supporting said head a substantial distance above said top part, the narrow portion of said slot accommodating said shank which engages a wall thereof in the closed position of said frame to hold said top part against outward movement and which is adjustable in the narrow portion of the slot to permit the lower part of the frame to be swung outwardly and the frame to be lowered bodily to a normal open position in which clearances are provided at its top and sides for ventilating purposes and in which said head engages said hanger to suspend said frame in said normal open position, said element being disengaged from said hanger to permit removal of the frame by swinging the lower part thereof further outwardly beyond said normal open position to enable said shank to be adjusted in said slot to a position which will permit said head to be withdrawn through said enlarged portion.

2. A hanger which is adapted to be secured to the header of a window casing for cooperation with the shank and head of an element carried by the top part of a frame of the character described, said hanger being angular, being attached to said header in such a manner that one section is substantially horizontal while another section is substantially vertical, and being formed with a continuous slot having a narrow portion located in said horizontal section and an enlarged portion located in said vertical section, the shank of said element supporting said head a substantial distance above said top part, and projections on said horizontal section adjacent the juncture of said horizontal and vertical sections and at opposite sides of the narrow portion of said slot, the narrow portion of said slot normally accommodating said shank which engages a wall thereof in the closed position of said frame to hold said top part against outward movement and which is adjustable in the narrow portion of the slot to permit the lower part of the frame to be swung outwardly and the frame to be lowered bodily to a normal open position in which clearances are provided at its top and sides for ventilating purposes and in which said head engages said hanger in front of said projections, said element being disengaged from said hanger to permit removal of the frame by swinging the lower part of the latter further outwardly beyond

said normal open position to enable said shank to be adjusted in said slot to a position which will permit said head to be elevated high enough to clear said projections and thereafter to be withdrawn through said enlarged portion.

3. A hanger which is adapted to be secured to the header of a window casing for cooperation with the shank and head of an element carried by a top part of a frame of the character described, said shank supporting said head a substantial distance above said top part and said hanger being formed with a continuous slot having a narrow front portion and a communicating enlarged rear portion, and projections at the opposite sides of said slot at the juncture of said narrow and enlarged portions, the narrow portion of said slot accommodating said shank which

engages a wall thereof in the closed position of said frame to hold said top part against outward movement and which is angularly and axially adjustable in the narrow portion of the slot to permit the frame to be swung outwardly and lowered to a normal open position in which clearances are provided at its top and sides for ventilating purposes and in which said head engages said hanger in front of said projections, said element being disengaged from said hanger to permit removal of the frame by swinging the latter further outwardly beyond said normal open position to enable said shank to be adjusted in the slot so that said head can be elevated to clear said projections and thereafter withdrawn through said enlarged portion.

GEORGE HUMMER.
